UNITED STATES PATENT OFFICE

LOUIS NACHMAN AND SAMUEL FINKELSTEIN, OF PHILADELPHIA, PENNSYLVANIA

ELASTIC-BAND STRUCTURE

Application filed December 8, 1927. Serial No. 238,486.

The object of our invention is to provide an elastic band structure especially adapted for use in garters, arm bands, belts and the like, wherein a flat elastic band is incased 5 within a pleated covering of tubular knitted fabric, whereby the pleated incasing fabric will expand and contract co-extensively with the expansion and contraction of the elastic band and, at the same time, provide an artistic and attractive outer surface.

Our invention also comprehends other features of construction which, together with those above enumerated, will be better understood by reference to the drawings, in which:

15 Fig. 1 is a transverse section through a piece of tubular knit fabric of relatively small diameter; Fig. 2 is a side view of a strip of our improved elastic fabric; Fig. 3 is a transverse section of the same; Fig. 4 is an edge 20 view of the fabric on a larger scale and with a portion of the tubular knitted casing cut away; Fig. 5 is a diagrammatic view illustrating the manner in which the tubular fabric is pleated before being assembled with the 25 elastic band; Fig. 6 is an edge view illustrating how the fabric may have its ends united, as in the case of garters and sleeve bands; Fig. 7 is a plan view of a garter, embodying 30 our invention; and Fig. 8 is a side view of a belt embodying our invention.

2 is a strip of tubular knit fabric which is flattened and run through pleating rolls which pleat the two-ply fabric so provided into a zigzag form, said rolls (not shown) 35 being heated during the pleating and pressing operation. The treatment in this manner is indicated in Fig. 5, wherein the pleating provides oppositely directed saw-tooth constructions as indicated at 3.

40 The tubular fabric, when so pleated, has its sides spread apart and a strip of flat elastic fabric 4 is inserted between the two connected plies, as will be clearly understood by reference to Figs. 2, 3 and 4. It will now be seen 45 that if such a fabric, as here indicated, is extended, not only will the elastic band 4 be stretched but the incasing tubular knitted fabric will also be extended with the extension of the elastic band, and reversely, will 50 contract and assume its former condition

when the elastic band is allowed to contract. The fabric is, therefore, as a whole, very elastic.

A fabric of this character may have the outer tubular part 2 formed of silk or other 55 artistic fiber to give a highly finished appearance, whereas the elastic portion may be constructed in a strong and more substantial manner and requiring no ornamentation.

In forming the tubular knitted fabric 2, it 60 may be made in any of the well known methods of knitting tubular fabrics and, moreover, may be knitted with threads of different colors and said colors may appear in spiral form about the tubular fabric and, 65 when pleated, provide a variegated or wavy design of an artistic nature.

A band of this character may be looped 70 into a circle, as indicated at 8, to form a garter or arm band, and the free ends may be secured in any suitable manner and ornamented. One manner of accomplishing this is to fold back the extreme ends upon themselves and unite them by a line of stitching, as indicated at 5 in Fig. 6, and such a seam may be 75 covered by an ornamental transverse band 7 decorated with a flower or ribbon design, as indicated at 6 in Fig. 7. We do not confine ourselves as to the manner of making such connection or ornamentation thereof.

80 When employed as a belt 9, the fabric strip embodying our improvements may be connected at one end to a buckle 10 and at the other end provided with a tip 11. There may be also the usual retaining bar 12 to receive 85 the end of the belt after passing through the buckle. When used for belt purposes, the elasticity of the band 4 may be very much less than that which is desirable when employing the improved fabric for garters or sleeve 90 bands.

95 Where greater firmness is desired between the tubular knitted and pleated casing part 3 and the elastic band part 4, one or more lines of stitching longitudinally of the article may be employed, as indicated in Fig. 2. In this case, we have indicated stitches 13 adjacent to the selvages or edges and at 14 along the middle. It will be understood that either or both of such lines of stitching may be em- 100

ployed. It is desirable that this stitching shall be done when the elastic band and the tubular knitted fabric are stretched, so that no strain will come upon the stitches in subsequent stretching of the article. The employment of these lines of stitches is to definitely position the tubular knitted fabric upon the elastic band to prevent any undue transverse movement of the tubular fabric about the core or elastic band 4, and to maintain the most desirable portions of the pleating upon the outside and inside of the fabric structure, where they best cooperate in the elasticity thereof.

15 It is also desirable that the tubular knitted fabric shall not have excessive elasticity, and in view of the fact that the extensibility is provided for by the pleating, the transverse elasticity may be made a minimum so as to 20 snugly fit the elastic band 4 at all times and reduce the freedom of transverse shifting of the tubular casing relatively to the elastic band.

It is further pointed out that, by reason 25 of the fact that the pleated knitted fabric when flattened into a two-ply structure, as indicated in Fig. 5, has the said plies spread apart sufficiently for the introduction of the flat elastic band 4, as indicated in Fig. 4, the 30 pleated plies will, from the nature of their structure, embody a yielding or cushioning quality and thereby give softness in contact with the wearer, even though the fibers of the threads employed in the knitting are of 35 a more or less stiff character suitable to retaining the accordion pleating which is impressed upon the fabric in accordance with this invention.

While we do not restrict ourselves in respect to the textile material of which the 40 knitted tubular fabric is made, it is preferable that the same shall be of a character that will assume the positive pleated form and retain it, and this result will be better secured where the fiber has a more or less hard 45 character, such as artificial silk and vegetable fibers.

It will now be apparent that we have devised a novel and useful construction which 50 embodies the features of advantage enumerated as desirable, and while we have in the present instance shown and described the preferred embodiment thereof which has been found in practice to give satisfactory 55 and reliable results, it is to be understood that we do not restrict ourselves to the details, as the same are susceptible of modification in various particulars without departing from the spirit or scope of the invention.

60 Having now described our invention, what we claim and desire to secure by Letters Patent is:

1. An elastic fabricated band for use in the manufacture of garters, sleeve bands, and 65 the like, comprising a seamless tubular

knitted fabric flattened into a two-ply band and transversely pleated along its whole length to give longitudinal extensibility at all portions of said length under tension and capacity to return to its original pleated length, 70 and a flat elastic band extending through the tubular knitted fabric and between the two flat pleated plies thereof, the length of the elastic band when not extended being approximately of the same length as the independent pleated tubular knitted fabric before being extended, and wherein further, the pleatings of the two plies of the seamless knitted fabric are respectively inclined in 75 opposite directions on the opposite sides of the flat elastic band and supported thereby.

2. The invention according to claim 1, wherein further, the pleatings of the two knitted plies are creased into oblique connecting relation over the edges of the flat 85 elastic band between said plies.

In testimony of which invention, we have hereunto set our hands.

LOUIS NACHMAN.

SAMUEL FINKELSTEIN.
